TYPE-WRITING MACHINE.

1,206,765.

Specification of Letters Patent. Patented Nov. 28, 1916.

Application filed October 4, 1915. Serial No. 53,884.

To all whom it may concern:

Be it known that I, JESSE A. B. SMITH, a citizen of the United States, residing in Brooklyn borough, in the county of Kings, 5 city and State of New York, have invented certain new and useful Improvements in Type-Writing Machines, of which the following is a specification.

This invention relates principally to type-writing machines, and more especially to machines of the general character shown in the patent to Wernery & Smith, No. 1,132,055. Such machine is adapted for writing on a number of superposed continuous 15 sheets, especially on webs folded longitudinally and intended to have written lengths or sections thereof to be torn off in cross-section from the body of the web, as for example, when the web comprises a series 20 of printed forms. In such work it is usual to employ ink-ribbons or carbon sheets interleaved with plies of the webs for making duplicate copies. After a section of web has been written, the platen is shifted away 25 from the usual feed-rollers to release the web and the interleaved carbon sheets, whereupon, by means of a carrier or holder the carbon sheets are drawn back along the web preparatory to printing on the succeeding 30 section of the web. The same carbon sheets are thus used repeatedly with the same web. The carbon-sheet-holder of a machine of this character is usually supported on a carriage which rides on a track provided on a frame or table attached to the 35 platen carriage. The table and carbon-sheet-holder therefore partake of the letter-feed and return movements of the platen carriage, while the carbon-sheet-holder has 40 also its own line-spacing and return movements on the table, but toward and away from the platen. The holder for the carbon sheets ordinarily comprises a set of fingers or clips to each of which the rear edge of a 45 carbon sheet is secured. These fingers protrude into the oppositely-directed folds of the web from opposite sides of the carriage, and are preferably stepped one above the other to permit of movement of transfer 50 material, without binding, when the same is shifted backwardly along the web. Here-

tofore the holding fingers have terminated at their free ends inside of the lines of the folds of the web, so as not to catch upon or tear the web.

It is sometimes desirable that the plies of the web, or at least some of the plies, be severed from one another in the machine, so that when a written length or section of web is removed, the plies thereof are already separated for distribution.

It is an object of the invention to effect such a separation of the plies of the web; and it is a further object of the invention to utilize the fingers, which hold the carbon 65 sheets, as the means by which the separation is effected. For this purpose, in the preferred form of the invention, the fingers, instead of terminating inside of the lines of the folds of the web, are extended across 70 those lines, and are shaped at their ends to form paper cutters. Commonly, to permit of easy separation of the plies of the web along correct lines, the web, as fed into the machine, is perforated along the lines of its 75 folds. When the web is thus perforated, the cutters of the present invention may be blunt paper-splitting devices. The severing of the plies by the fingers which hold the carbon sheets takes place when the fingers 80 are moved backwardly along the web by their carriage in re-positioning the carbon sheets for the writing of a new section of the web. The cutting edges are therefore preferably inclined backwardly and inwardly across the lines of the folds. As it may not be desired to separate all of the plies, certain only of the fingers which hold the carbon sheets need carry cutters.

Other features and advantages will hereinafter appear.

In the accompanying drawings, Figure 1 is a perspective view of a construction embodying the invention as applied to an Underwood typewriting machine, the parts being in position to permit writing upon a work-piece. Fig. 2 is a fragmentary perspective view of one of the clips or fingers for holding a sheet of transfer material, the web-cutter or separator of the present invention being shown on the end of the clip. Fig. 3 is a view in cross-section through the

web, showing the manner in which it is folded, and showing one of the clips in position to cut the edges of the web at one of the folds thereof. Fig. 4 is a plan view of 5 a fragment of the web; the cutting blades being also shown in position for cutting.

Referring particularly to Fig. 1, which shows the general arrangement of the platen carriage, carbon-sheet-holder, and means for 10 unfolding or straightening the web to permit the carbon sheets to be retracted; the platen 10 is fixed to a platen shaft 11 journaled in arms 14 and 15 of a frame fast to a rock shaft 12. The shaft 12 has bearings

15 in the ends 13 of the usual platen frame. The swinging frame is normally held in the Fig. 1 position for writing, with the platen down against the usual front feed-rolls (not shown), and may be swung from this position to its web-releasing position by means of an arm 16 fast to the rock shaft 12, and provided with a handle 16^a. For locking the swinging frame in the Fig. 1 position, the arm 16 carries a pin 17 adapted to be 20 engaged by a hook 18 pivotally mounted on the platen frame end 13. A spring 19 yieldingly holds the hook in operative position, and in returning the parts to such position, the pin 17 cams back the hook so that the 25 locking may be automatic. A tooth 20 on the hook, together with a pin 22 on the right-hand end 13 of the platen frame, determines the return throw and normal position of the swinging frame.

30 The platen may be rotated by the usual hand wheel 24, or the line-space ratchet wheel 25, both fast to a short shaft 26 mounted to rotate in the left-hand end 13 of the platen frame. When the platen is in printing position the shaft 26 is in alinement with the shaft 11. As is common in Underwood typewriting machines, the ratchet wheel is actuated by a pawl 27 on the usual slide 29 engaged by one arm of a line-space lever 35 (not shown), on the carriage frame. A 35 spring-actuated detent 34 engages the ratchet wheel to hold the platen against rotary displacement. The driving connection between the shaft 26, whose axis is stationary, and the platen shaft 11, which swings upwardly from normal position, consists of gears 35, 36 and 37. The gear 35 is fast on the shaft 26, the gear 36 is fast on the platen shaft, and of the same diameter and provided with 40 the same number of gear teeth as the gear 35, and the gear 37 is loose on the axle 12, around which the platen swings as an axis, the gear 37 having a face of sufficient width to mesh with both gears 35 and 36. The 45 driving connection between the shaft 26 and the platen is thus maintained in all positions of the platen.

In the operation of removing a printed length from the webs and in readjusting the

carbons for printing the next length, the 65 platen is swung from printing position away from the feed-rolls, so that the webs and carbon sheets are no longer wrapped around the platen, and the carbon sheets may be moved freely between the webs to return 70 them to a position opposite a succeeding portion of the webs. The webs are formed from a single piece fan-folded longitudinally to provide for several copies when the carbon sheets are interleaved with the folds. 75 The edges along which the folds are made are preferably perforated to permit of easy detachment of one ply from another.

The webs may be fed into the machine over the rear rail 38 of a table 39, the side 80 rails 40 of which are further connected and braced by cross bars 41 and 42, and, at the front of the machine, by a rod 43 journaled in bracket arms 44 in the platen carriage, so that the table may be folded up when desired. The table is secured to the platen carriage to have letter-feed and return movement with the latter. The cross bar 41 carries a roller 45, which rides and supports the table on a rail 46 carried by a framework 90 47 secured to the main frame of the machine. As the web passes on to the table, the folds or plies thereof are separated and guided by fingers 48, secured to the machine at both sides thereof. The fingers 48 at one 95 side of the machine are staggered with respect to those at the other side, alternate fingers being secured to the same side of the machine, so that the fingers may project into the oppositely directed fan-folds of the web. 100 A pair of guides 49 for the edges of the web may also be secured to the rail 38. From the rail 38 the web is led forwardly over the table and over a tie-rod 50 of the platen carriage, thence down around the platen between the latter and the feed-rolls, up past the printing line, under the cutter 51, and onto the paper shelf 52 between the side edge gages 53. When the handle 16^a is thrown to release the web, written lengths thereof 105 may be measured by drawing the web to the gage 54, carried by the bar 55 on the paper shelf, and may then be severed by drawing the web against the cutter 51. The cutter is shown as a plate secured to a sleeve 56 on the shaft 12; to which sleeve is also secured a finger 57 for rocking the cutter into engagement with the web when the latter is to be cut. The printing on the web is effected by types 58 which may be operated by the 110 usual mechanism.

The carbon sheets, by means of the binding action thereon of the webs, due to the feed-rollers, are caused to advance with the webs at each line-space turn of the platen; 115 and, when the platen is shifted upwardly, as before noted, the carbon sheets are released and may be drawn back along the webs from

the written to the next unwritten length thereof. To provide for these movements of the carbon sheets, the same, in machines of this character, are attached at their rear edges to a traveling holder or carriage on the table 39. This carriage 59 may comprise a body portion or plate having a stepped block 60 at each side thereof. Fingers or clips 61 to each of which one carbon sheet may be attached, are secured by screws 62 to the steps 63 of the blocks 60. The fingers 61, like the fingers 48, are staggered upwardly, alternate fingers being secured to the same side of the carriage 59, so that the oppositely-directed fan-folds of the web may each receive a finger.

Depending plates 64, secured to the ends of the carriage plate 59, each carry a pair of vertically disposed rollers 65, adapted to ride on horizontal flanges 66 on the side rails 40 of the table 39. Other horizontal flanges 67 on the table side rails overlie the rollers and hold the carriage to the table. For throwing back the carriage to move the carbon sheets backwardly along the web, there is attached to the left-hand block 60, a handle 68.

The carbon-holding fingers 61 have heretofore terminated, at their free ends, inside of the margin or side edge of the web, so as not to catch upon the web. In the preferred form of the present invention, however, these fingers are conveniently used as means for cutting the web at the folds thereof, so that the written length of the web, prior to its detachment from the rest of the web, may have certain, or all, of the plies thereof separated from one another. For this purpose, the fingers 61, or such of them as lie between plies which are to be cut apart, have their free ends in the form of cutters 69, which cross the line of the side edge of the web. As already stated, when a section of web has been written, the web is released from the feed-rollers and is drawn by hand to the gage 54; and, while the web is so released and held by hand, the carriage 59 is moved backwardly in order to position the carbon sheets in the length of web next to be written. This backward movement of the carriage 59 causes the cutters 69 to sever the plies of the web for a distance therealong determined by the movement of the carriage in bringing the carbon sheets to initial position. The cutting edges are preferably inclined inwardly and backwardly, as shown in the drawings, so as to split the web without tearing, crumpling or displacing it. When the web is fed into the machine with its edges already perforated, a relatively blunt cutting edge may be used. In the form shown, the cutter consists of an inclined bead 70 which is extended as a pin or lug on the end of the finger 61.

Variations may be resorted to within the scope of the invention, and portions of the improvements may be used without others.

Having thus described my invention, I claim:

1. In a typewriting machine, a platen, means for effecting a line-space feed to the platen of a work-piece folded on a line extending in the direction of such feed, means for supporting and guiding the work-piece as it is fed to the platen, and means at the line of said fold arranged to sever, one from another, the plies of the work-piece.

2. In a typewriting machine, a platen, means for effecting a line-space feed to the platen of a work-piece folded on a line extending in the direction of such feed, means for supporting and guiding the work-piece as it is fed to the platen, and a knife movable relatively to the work-piece on the line of said fold for severing, one from another, the plies of the work-piece.

3. In a typewriting machine, a platen, means for effecting a line-space feed to the platen of a work-piece folded on a line extending in the direction of such feed, means for supporting and guiding the work-piece as it is fed to the platen, means interposed between the plies of the work-piece for holding the plies apart, and a device carried by said interposed means for splitting the work-piece on the line of its fold.

4. In a typewriting machine, a platen, means for effecting a line-space feed to the platen of a work-piece folded on a line extending in the direction of such feed, means for supporting and guiding the work-piece as it is fed to the platen, and a knife movable backwardly along the work-piece on the line of said fold for severing, one from another, the plies of the work-piece.

5. In a typewriting machine, a platen, means for effecting a line-space feed to the platen of a work-piece folded on a line extending in the direction of such feed, a carriage for holding transfer material between the plies of the work-piece during line-space feed of the transfer material with the work-piece and for shifting the transfer material at intervals backwardly along the work-piece, and means on said carriage for severing, one from another, the plies of the work-piece.

6. In a typewriting machine, a platen, means for effecting a line-space feed to the platen of a work-piece folded on a line extending in the direction of such feed, a carriage for holding transfer material between the plies of the work-piece during line-space feed of the transfer material with the work-piece and for shifting the transfer material at intervals backwardly along the work-piece, and means on said carriage for severing, one from another, the plies of the work-piece.

work-piece, when the carriage shifts the transfer material backwardly.

7. In a typewriting machine, a platen, means for effecting a line-space feed to the platen of a work-piece folded on a line extending in the direction of such feed, a clip for holding transfer material between the plies of the work-piece, a carriage for said clip movable toward the platen to permit of line-space feed of the transfer material with the work-piece and movable away from the platen to re-position the transfer material on the work-piece, and means on said clip for severing, one from another, the plies of the work-piece.

8. In a typewriting machine, a platen, means for effecting a line-space feed to the platen of a work-piece folded on a line extending in the direction of such feed, a clip for holding transfer material between the plies of the work-piece, a carriage for said clip movable toward the platen to permit of line-space feed of the transfer material with the work-piece and movable away from the platen to re-position the transfer material on the work-piece, and means on said clip for severing, one from another, the plies of the work-piece, during the re-positioning movement of the carriage.

9. In a typewriting machine, a platen, means for effecting a line-space feed to the platen of a work-piece, folded on a line extending in the direction of such feed, a clip for holding transfer material between the plies of the work-piece, and a carriage for said clip movable toward the platen to permit of line-space feed of the transfer material with the work-piece and movable away from the platen to re-position the transfer material on the work-piece, said clip being extended across the line of the fold of the work-piece to sever the work-piece at such fold.

10. In a typewriting machine, a platen, means for effecting a line-space feed to the platen of a work-piece folded on a line extending in the direction of such feed, a clip for holding transfer material between the plies of the work-piece, and a carriage for said clip movable toward the platen to permit of line-space feed of the transfer material with the work-piece and movable away from the platen to re-position the transfer material on the work-piece, said clip carrying a paper cutter, the edge of which is inclined backwardly and inwardly across the line of the fold of the work-piece to sever the latter at said fold during the backward movement of the carriage.

11. In a typewriting machine, a platen, means for effecting a line-space feed to the platen of a work-piece folded zig-zag, or fan-folded, on lines extending in the direction of such feed, clips for holding transfer

material between the plies of the work-piece, 65 said clips protruding from opposite sides of the work-piece into the oppositely directed folds thereof, a carriage for said clips movable toward the platen to permit of line-space feed of the transfer material with the 70 work-piece and movable away from the platen to re-position the transfer material on the work-piece, and means on said clips for severing, one from another, the plies of the work-piece.

12. In a typewriting machine, a revoluble platen, means for effecting letter-feed movement thereof, means for effecting line-space feed to the platen of a work-piece folded on a line extending in the direction of such 80 line-space feed, a table connected to the platen to have letter-feed movement therewith, a carriage on said table for holding transfer material between the plies of the work-piece, said carriage being movable toward the platen to permit of line-space feed of the transfer material with the work-piece and being movable away from the platen to re-position the transfer material on the work-piece, and means on the carriage for severing, one from another, the plies of the work-piece.

13. In a typewriting machine, the combination with a platen, of means for feeding to the platen a work-piece folded on a line 95 extending in the direction in which the work-piece is fed, means for holding transfer material between the plies of the work-piece to be advanced with the work-piece, and for shifting the transfer material at 100 intervals backwardly along the work-piece, and means operable automatically to sever, one from another, the plies of the work-piece concomitantly with the shifting of the transfer material backwardly.

14. In a typewriting machine, the combination with a platen, of means for feeding to the platen a work-piece folded zig-zag on lines extending in the direction of such feed, and clips for holding sheets of 110 transfer material between the plies of the work-piece, said clips protruding from opposite sides of the work-piece into the oppositely directed folds thereof, each of said clips carrying a severing-blade, the edge of 115 which is inclined backwardly and inwardly across the line of the fold of the work-piece, whereby, during the backward movement of the carriage, said blades are effective to sever, one from another, the plies of the 120 work-piece, and also apply to the said plies an outward pressure along said folds, whereby creasing, crumpling or displacement of the work-piece is prevented.

15. In a typewriting machine, the combination with a platen, of means providing a web course for a work-piece or web, folded lengthwise, and arranged to be fed past the

printing line at the platen, a web-severing blade, and means for effecting a relative movement of the blade and the web in a direction lengthwise of the web for severing the latter at said fold, said blade extending diagonally across the fold with the inner edge thereof in advance of the outer edge with respect to the direction of movement of the blade relative to the web.
